BOONE V. H. JOHNSON

BY *J. R. Carnes, Atty.*

UNITED STATES PATENT OFFICE.

BOONE V. H. JOHNSON, OF ST. LOUIS, MISSOURI, ASSIGNOR TO DOUBLE BODY BOLSTER COMPANY, OF ST. LOUIS, MISSOURI, A CORPORATION OF NEW JERSEY.

COMBINED CAR-BODY CORNER-POST AND DOOR-FRAME.

1,064,970.

Specification of Letters Patent. Patented June 17, 1913.

Original application filed April 29, 1911, Serial No. 624,166. Divided and this application filed April 11, 1912. Serial No. 689,958.

To all whom it may concern:

Be it known that I, BOONE V. H. JOHNSON, a citizen of the United States, residing at St. Louis, Missouri, have invented a certain new and useful Improvement in Combined Car-Body Corner-Posts and Door-Frames, of which the following is a full, clear, and exact description, such as will enable others skilled in the art to which it applies to make and use the same, reference being had to the accompanying drawings, forming part of this specification, in which—

Figure 1 is a perspective view showing the end of a passenger coach or car in dotted lines with my improved combined corner post and door frame applied thereto. Fig. 2 is a horizontal section taken approximately on the line 2—2 of Fig. 1. Fig. 3 is a vertical section taken approximately on the line 3—3 of Fig. 1. Fig. 4 is a perspective view of a modified form of the combined corner post and door frame.

This invention relates generally to railway passenger cars and more particularly to the car end construction, my principal object being to provide a simple, strong and comparatively light one-piece structure which is preferably cast and which combines a car body corner post and door frame.

A further object of my invention is to provide a car end frame reinforcing and bracing member that can be advantageously employed in connection with all types of car bodies for the purpose of bracing the upright end frames of the superstructure and materially strengthening the ends of the cars, thereby providing a strong, substantial structure which will resist severe end shocks due to collisions and resisting all tendency of the cars to telescope, thus affording a maximum degree of safety to life and property.

In order to overcome the tendency of car bodies to telescope during collisions various metal structures have been devised and are at present in general use, which structures include cast metal underframes, platforms, buffing sills and one-piece end frames which latter structures are of the type shown in Patents #917,716, dated April 6, 1909 and #929,705, dated August 3, 1909.

To further strengthen and reinforce the ends of car bodies and the vertically dis-

posed end frames applied thereto so as to reduce to a minimum the tendency of said bodies to telescope during collisions and to effectually resist all end shocks and buffing stresses I propose to provide a metal post or upright member to be applied directly to the corner of a car body preferably behind or inside the upright end frame forming a part of said car body, and to form with said post a door frame which occupies a position between the corner post and the end of the buffer beam.

The combined corner post and door frame herein shown and described is particularly designed for use in connection with combined double body bolsters and platforms of the type shown in Patent #774,474, and the one-piece cast metal end frames of the type shown in Patents #917,716 and 929,705.

This application is a division of an application filed by me April 29, 1911, Serial #624,166.

To the above purposes my invention consists in certain features of novelty herein-after more fully described and claimed.

Referring by numerals to the accompanying drawings; 1 designates the car body, 2 the underframe, 3 the platform, 4 the steps at the sides of said platform and 5 the end frame, all of which parts are of ordinary well-known construction in the car-builders' art.

My improved construction as shown comprises an upright or post 6 which is preferably L-shaped in cross section, and when said post is applied for use, the inwardly projecting flange 6^a occupies a position between the upright end frame of the car body or superstructure and the end portions of the side frames and walls of said car body, thereby bearing directly against the inner or rear faces of the side portions of said upright car end frame so as to form an effective brace therefor and to distribute over a considerable area of the side portions of the end of the car body all end shocks and crushing stresses which may be imparted to the upright car end frame.

Formed integral with the lower portion of the post 6 is a horizontally disposed rail 7 preferably of inverted L-shape in cross section and when applied for use the horizontally disposed flange of this rail bears directly against the top of the underframe

2. Extending from the end of this rail or member 7 to the upper portion of the post or upright 6 is a diagonally disposed brace 8.

5 Formed integral with the upper and lower ends of the post or upright 6 are upper and lower rails 9 and 10 respectively, which form the lintel and threshold plates of the door frame. Both of these members are 10 preferably L-shape in cross section with their horizontally disposed flanges projecting inwardly, and uniting the outer ends of this lintel and threshold plate is a vertically disposed post or upright 11 preferably 15 L-shape in cross section, and said post or upright is fixed to and forms a substantial upright between the end of the buffing sill and the outer corner of the car hood.

The posts 6 and 11 extend below the plane 20 occupied by the underframe 2 and platform 3 so that the threshold plate 10 arranged between the lower ends of said posts readily combines with the lower one of the car steps 4.

25 In the modified construction illustrated in Fig. 4, a diagonally disposed bracing member 12 is arranged between the end of the rail 7, and the central portion of the post or upright 6 and a diagonally disposed member 13 is arranged between the end of the rail 7 and the lower end of said post or upright 6.

30 My improved reinforcing and strengthening structure is preferably cast in a single 35 piece so that it can be readily applied for use and when properly combined with a car body and the upright end frame thereof, said structure provides a very strong and comparatively light construction which 40 combines with the end frame of the car body in resisting all end shocks and stresses due to collisions, thereby minimizing the danger of telescoping of the cars due to 45 collisions while said cars are running at high speed.

The braced corner post 6 being positioned to the rear of the car end frame materially strengthens the car end and corner between the underframe and the superstructure, and 50 by providing the inwardly projecting flanges 6^a all stresses and shocks imparted to the upright end frame of the car body are distributed over a considerable area of the car body superstructure.

55 In practice, I prefer to form the inwardly projecting flange 6^a of the corner post substantially wider than the side flange, which arrangement is clearly shown in Figs. 1 and 2.

60 The corner post is further braced against crushing stresses and end shocks by the diagonally disposed braces between said corner post and the end of the rail 7, and this construction combined with the extra wide 65 flange projecting inwardly from the corner

post is effective in resisting all crushing stresses which may be imparted direct to the upright end frame of the car body or superstructure, which end frame, as shown and described, is preferably arranged so that 70 the inner faces of its side edges bear directly against the wide, inwardly projecting flanges 6^a of the corner posts.

It will be readily understood that minor 75 changes in the size, form and construction of the various parts of my improved reinforcing corner post may be made and substituted for those herein shown and described without departing from the spirit of my invention, the scope of which is set forth 80 in the appended claims.

I claim:

1. A combined car body corner post and 85 door frame comprising a vertically disposed flanged member adapted to be positioned behind the car end frame at the corner of the car body, a horizontally disposed flanged member extending inwardly from the lower portion of the vertically disposed member, which horizontally disposed member is 90 adapted to engage the underframe of the car body, horizontally disposed rails integral with the ends of the vertically disposed member, and a platform side door post connecting the outer ends of the last mentioned 95 horizontally disposed members.

2. A combined car body corner post and 100 door frame comprising a vertically disposed flanged member adapted to be positioned behind the car end frame at the corner of the car body, a horizontally disposed flanged member extending inwardly from the lower portion of the vertically disposed member, which horizontally disposed member is 105 adapted to engage the underframe of the car body, a brace between the vertically disposed and horizontally disposed members, horizontally disposed rails integral with the ends of the vertically disposed member, and a platform side door post connecting the 110 outer ends of the last mentioned horizontally disposed members.

3. A combined car body door post and 115 door frame comprising an upright member adapted to be positioned behind the end frame at the corner of the car body, an inwardly projecting flange integral with said member, which flange is adapted to engage the end frame of the car body, a horizontally disposed rail integral with the lower 120 portion of the vertically disposed member for engaging the underframe of the car body top and bottom rails integral with the ends of the vertically disposed member, and a vertically disposed member integral with the 125 outer ends of the horizontally disposed top and bottom members.

4. A combined car body door post and 130 door frame comprising an upright member adapted to engage the end framing at the

- corner of a car body, an inwardly projecting flange integral with said member, which flange is adapted to be positioned behind the end frame of the car body, a horizontally disposed rail integral with the lower portion of the vertically disposed member for engaging the underframe of the car body, an integral brace disposed between the vertical and horizontal members, top and bottom rails integral with the ends of the vertically disposed member, and a vertically disposed member integral with the outer ends of the horizontally disposed top and bottom members.
- 5 10 15 20 25 30 35 40 45 50 55 60 65 70 75 80 85 90 95 100 105 110 115
5. The combination with a car body and its end frame, of a reinforcing corner post applied to the corner of the car body, a portion of which post is positioned behind the car body end frame, a horizontally disposed flanged member at the lower end of said reinforcing corner post, top and bottom rails integral with the corner post, and a platform side door post integral with the top and bottom rails.
6. The combination with a car body and its end frame, of a reinforcing corner post applied to the corner of the car body, a portion of which post is positioned behind the car body end frame, a horizontally disposed flanged member at the lower end of said reinforcing corner post, a brace between the corner post and the horizontally disposed flanged member, top and bottom rails integral with the corner post, and a platform side door post integral with the top and bottom rails.
7. The combination with a car body and its end frame, of a reinforcing member applied to the end corner of the car body, which member comprises a braced post, a portion of which is positioned behind the end frame of the car body upper and lower rails integral with said post, and a platform side door post integral with the ends of said upper and lower rails.
8. The combination with a car body and its end frame, of a post applied to the corner of the car body behind the end frame thereof, a flanged member integral with said post, which flanged member engages the underframe of the car body upper and lower rails integral with the post, which upper and lower rails form the lintel and sill of the platform side door frame, and an upright connecting the outer ends of said upper and lower rails.
9. As a new article of manufacture, a reinforcing corner post for the transversely disposed upright end frames of car bodies comprising an upright member adapted to be applied to the corner of a car body, and an end platform side door frame integral with said flanged upright.
10. As a new article of manufacture, a reinforcing corner post for the transversely disposed upright end frames of car bodies comprising an upright member adapted to be applied to the corner of a car body, an end platform side door frame integral with said flanged upright.
11. As a new article of manufacture, a reinforcing corner post for the transversely disposed upright end frames of car bodies comprising an upright member adapted to be applied to the corner of a car body, an end platform side door frame integral with said upright, and a brace for said upright member.
12. As a new article of manufacture, a reinforcing corner post for the transversely disposed flanged upright end frames of car bodies comprising an upright member adapted to be applied to the corner of a car body, an end platform side door frame integral with said flanged upright, and a brace for said flanged upright.
13. As a new article of manufacture, a reinforcing member for the transversely disposed upright end frames of car bodies of a flanged upright adapted to be applied to the corner of the car body and engage the side portion of the transversely disposed end frame, an end platform side door frame rigidly fixed to said upright, a horizontally disposed rail fixed to said upright and adapted to engage a part of the car underframe, and a brace between the horizontally disposed rail and flanged upright.
14. A reinforcing member for the corner portions of car bodies and the transversely disposed upright end frames thereof comprising a flanged upright adapted to engage the end corner of the car body and the side portion of the transversely disposed end frame, flanged top and bottom rails integral with said flanged upright, a flanged post integral with said top and bottom rails, which flanged upright, top and bottom rails and flanged post form a car end platform side door frame, a horizontally disposed flanged rail integral with the flanged upright, which last mentioned rail is adapted to engage a portion of the car underframe, and a brace between said last mentioned rail and the flanged upright.
- In testimony whereof I hereunto affix my signature in the presence of two witnesses, this 14th day of March, 1912.
